(57) **CLAIM**

The ornamental design for a shoe hanger, as shown and described.

DESCRIPTION

FIG. 1 is a front elevation view of a shoe hanger in its environment;

FIG. 2 is a front elevation view of the shoe hanger;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in FIG. 1 illustrate environmental structure and form no part of the claimed design.

1 Claim, 5 Drawing Sheets
